SKI-SLED OR SIMILAR ARTICLE

William F. Davis, 107 Brown St.,
Tecumseh, Mich. 49286

Filed July 1, 1970, Ser. No. 23,775

Term of patent 14 years

Int. Cl. D21—02

U.S. Cl. D34—15

FIG. 1

FIG. 4

FIG. 2

FIG. 5

FIG. 1 is a right side elevational view of the ski-sled showing my new design, the left side being a mirror image thereof; and

FIG. 2 is a front elevational view of FIG. 1; and

FIG. 3 is a rear elevational view thereof; and

FIG. 4 is a top plan view thereof; and

FIG. 5 is a bottom plan view thereof.

I claim:

The ornamental design for a ski-sled or similar article, substantially as shown and described.
